ATTORNEY

UNITED STATES PATENT OFFICE.

WELDON A. L. HOFF, OF EDMOND, OKLAHOMA.

ADJUSTABLE CRUTCH-TIP.

1,197,375.

Specification of Letters Patent. Patented Sept. 5, 1916.

Application filed December 22, 1915. Serial No. 68,262.

To all whom it may concern:

Be it known that I, WELDON A. L. HOFF, a citizen of the United States, residing at Edmond, in the county of Oklahoma and 5 State of Oklahoma, have invented certain new and useful Improvements in Adjustable Crutch-Tips, of which the following is a specification.

This invention relates to an improved 10 crutch and the principal object of the invention is to provide an improved type of crutch end, the resilient core thereof being adjustably held in place by improved means whereby the core can be gradually fed out 5 of the lower end portion of the crutch.

Another object of the invention is to so 20 construct this crutch that when the core is worn out, a new one can be easily put in place.

25 This invention is illustrated in the accompanying drawings, wherein:—

Figure 1 is a view showing the improved 30 crutch in elevation. Fig. 2 is an enlarged 25 sectional view through the lower portion of the crutch.

This crutch is provided with the side bars 35 10 connected by the hand grip 11 and having their lower ends secured in the sleeve 12. This sleeve 12 may be connected with the 40 side bars 10 in any suitable manner as the subject matter of this invention relates to the manner of adjustably holding the core 45 13 within the sleeve. This core 13 which is preferably formed of rubber, fits within the 50 lower end portion of sleeve 12 and is provided at its upper end with openings through 55 which the wires 14 pass. These wires 14 are bent to engage the head 15 of the inner sleeve 16 through the openings 17 and it will 60 thus be seen that the core will be securely 65 connected with the sleeve 16. This sleeve 16 is provided with a plurality of openings 70 18 extending in spiral courses around the sleeve, each of the openings being positioned 75 diametrically opposite a second opening, so 80 that the bolt 19 can be passed through the 85 sleeve 12 and through a selected set of the 90 openings 18. By having the openings 18 extend in spiral courses around the sleeve 95 16, the sleeve 16 can be adjusted longitudi-

nally in sleeve 12 for a small distance. As 55 the core is worn off, the core will be drawn outwardly and when extended as far as desired, the bolt replaced. When the core is entirely worn out a new core can be obtained 60 and either by using the same wires 14 or by using new wires, this core can be connected with the sleeve 16 and put in place. It will thus be seen that the new core 65 can be easily and quickly substituted for the worn out one and further that the core can be easily and quickly adjusted. This will permit the crutch to be regulated according to the length desired. It very often 70 happens that a crutch will be either just a little too long or a little too short but with this construction, the exact length can be 75 readily obtained.

What is claimed is:—

1. A crutch including a terminal sleeve, 70 a carrying sleeve slidably mounted in said terminal sleeve and provided with a head at its lower end and having its walls provided with openings adjacent the head, a core fitting within said terminal sleeve, wires 75 passed through said core and having their end portions bent upwardly and passing through the openings in the walls of said carrying sleeve to engage the head thereof and releasably connect the core with the 80 carrying sleeve, and means for releasably holding said carrying sleeve in an adjusted position within said terminal sleeve.

2. A support including a terminal sleeve, 85 a carrying sleeve adjustably mounted in said terminal sleeve and having walls provided with openings adjacent its lower end, a core positioned beneath said carrying sleeve in said terminal sleeve and extending out of said terminal sleeve, and pliable means 90 passing through said core and having its end portions passed through the openings in the carrying sleeve to connect the core with the lower end of the carrying sleeve.

In testimony whereof I affix my signature 95 in presence of two witnesses.

WELDON A. L. HOFF.
